UNITED STATES PATENT OFFICE.

FRED M. WELD, OF ATTLEBORO, MASSACHUSETTS.

MOLD FOR CASTING JOURNAL-BOX LININGS.

SPECIFICATION forming part of Letters Patent No. 683,824, dated October 1, 1901.

Application filed March 11, 1901. Serial No. 50,658. (No model.)

To all whom it may concern:

Be it known that I, FRED M. WELD, a citizen of the United States, and a resident of Attleboro, in the county of Bristol and State of Massachusetts, have invented a new and useful Improvement in Molds for Casting Journal-Box Linings, of which the following is a specification.

This invention has reference to an improvement in molds for casting the linings into journal-boxes.

Journal-boxes are usually lined with Babbitt or other compound metal linings. It is desirable to cast these linings into the journal-boxes so perfect and complete that little or no finishing is required.

The object of this invention is to facilitate the casting of the linings into the journal-boxes; and to this end the invention consists in the peculiar and novel construction and the combination of the parts whereby linings may be cast into the journal-boxes complete with the required thickness of the projecting end flange, as will be more fully set forth herein-after.

Figure 1 is a front view of my improved mold. Fig. 2 is a side view of the same with parts in section. Fig. 3 is a transverse sectional view, and Fig. 4 is a vertical sectional view, of the mold, which is shown in all the figures as closed ready for casting the lining into one half of the journal-box.

In the drawings, *a* indicates the base, and *a'* the back plate of the mold. The brackets *a²* project from the rear of the back plate *a'*. The core *b* is secured to the front of the back plate *a'* by the screws *b' b'*. The half *c* of the journal-box into which the lining is to be cast has usually on its lower end the flange *c'* and bears along its longitudinal edges against the front face of the back plate *a'*, one edge bearing against the stop-plate *c²*, secured to the face of the back plate. The half of the journal-box when adjusted to the stop-plate *c²* is secured by the clamping-lever *d*, hinged on one side to a bracket and secured by engaging with the ratchet-teeth of the arm *d'*. The space between the lower end of the half *c* and the base *a* is closed by the band *d²*, of flexible sheet metal. The band *d²* is secured at one end to the back plate *a'*. It extends around the flange *c'* and has the other

end secured to the lever *d³*. A strong spiral spring *d⁴* is interposed between the band *d²* and the lever *d³*. When the band *d²* is 55 tightly stretched, the lever is secured by engaging with a fixed ratchet *a⁴*, as is shown in Fig. 2. A funnel-shaped gate *e* is formed partly in the core and partly in the piece *c³*, provided with the handle *c⁴*. The piece *c³* 60 closely fits the core *b*, except at the portion forming the gate *e*.

In casting the piece *c³* is placed onto the half of the journal-box and against the core. When the casting is completed, the lever *d³* 65 and the clamping-lever *d* are released. The half *c* of the journal-box is now pushed outward by the cams *f f'*, acting on the posts *f' f'*, which extend through the back plate *a'* and bear against the edges of the half of the journal-box, as is shown in Fig. 3. The cams *f f'* are secured to the shafts *f² f²*, journaled in the brackets *a² a²*, and are operated by the lever *f³*, secured to the lower shaft *f²*, and the lever *f⁴*, secured to the upper shaft *f²* and 75 connected with the lever *f³*, so that all the cams will operate simultaneously to move the journal-box, now provided with a lining, away from the core. A spring *f⁵* is coiled on each shaft *f²* to return the cams *f* to normal position. Only the slight fin of the gate *e* requires to be broken off to complete the journal-box. The core *b* may be removed and replaced by another core and the stop-plate *c²* replaced by another when journal-boxes of different dimensions require to be lined.

Having thus described my invention, I claim as new and desire to secure by Letters Patent—

1. A mold for casting the linings into journal-boxes having a base and back plate, a removable core secured to the back plate, means for securing a half of a journal-box against the face of the back plate, and means for 95 loosening the box after casting the lining comprising a plurality of shafts, a lever connected to the shafts for operating them, cams on the shafts, and posts extending through the back plate, as described.

2. In a mold for casting the linings into journal-boxes, the combination with the base, the back plate and the core secured to the back plate, of a stop-plate for gaging the po-

sition of the journal-box, a clamping-lever for securing the box to the back plate, a flexible band for closing the space between the end of the box and the base-plate, a detachable gate-piece, and means for loosening the box after casting the lining comprising a plurality of shafts, a lever connected to the shafts for operating them, cams on the shafts, and stops extending through the back plate, as described.

3. In a mold for casting the linings into journal-boxes, the combination with the base a , the back plate a' , the core b detachably secured to the back plate, and the posts $f' f'$

supported in the back plate, of the brackets a^2 , the shafts $f^2 f^2$ journaled in the brackets, the cams $f f$ on the shafts, the levers f^3 and f^4 secured to the two shafts and connected together, and means substantially as described for securing the journal-box half to be lined to the back plate, as described.

In testimony whereof I have signed my name to this specification in the presence of two subscribing witnesses.

FRED M. WELD.
